UNITED STATES PATENT OFFICE.

EDWARD W. GRANT, OF YPSILANTI, MICHIGAN.

CAR-COUPING.

SPECIFICATION forming part of Letters Patent No. 244,888, dated July 26, 1881.

Application filed June 13, 1881. (No. model.)

To all whom it may concern :

Be it known that I, EDWARD W. GRANT, of Ypsilanti, in the State of Michigan, have invented certain new and useful Improvements 5 in Car-Couplings; and I do hereby declare that the following is a full, clear, and exact description thereof, reference being had to the accompanying drawings, and to the letters of reference marked thereon, which form part of 10 this specification, and in which—

Figure 1 is a longitudinal section, showing the pin raised; Fig. 2, a similar view with the pin lowered; and Fig. 3 a detail, showing the different parts of the coupling devices.

15 The primary object of this invention is to provide means for retaining the coupling-pin in a raised position and automatically releasing it and allowing it to drop, by the action of the link against a weighted and pivoted catch; 20 and to this end it consists in the combination, with a draw-head, of a pivoted bifurcated latch, a weighted and pivoted catch, and a coupling-pin, all constructed and arranged to operate substantially in the manner hereinafter set 25 forth and claimed.

In order that others skilled in the art may avail themselves of the benefits of my invention, I will now particularly describe its construction and operation.

30 A represents the draw-head, which may be of the usual form, and provided on its upper side with ears or lugs *a a* and on its under side with ears or lugs *a' a'*.

Between the lugs *a a* is pivoted the latch B. 35 This latch is bifurcated at its front end, and between its prongs is removably pivoted the coupling-pin *b*. The rear end of the latch B is formed with a small projection, which is turned upward, so that when the pin is elevated, as seen in Fig. 1, its upper face will be about on a level with the upper side of the draw-head.

C represents a catch, which is placed in and extend through a slot in the draw-head be-

tween the lugs *a a* and *a' a'*, and is pivoted between the latter. The lower end of this catch is curved or bent forward and weighted in order to throw the upper end forward to engage or hold the latch B when it is desirable to have the pin in an elevated position. The pin being raised the upper hooked end of the catch C is thrown forward and engages with the projecting end of the latch B, holding it in a raised position. If, now, it is desired to couple the cars, the link entering the draw-head strikes the weighted catch, thus releasing the latch B and pin *b* and allowing them to drop into place, automatically coupling the cars.

It will be observed that the head of catch C is beveled in order to rest under and against the projecting end of the latch B when the pin is down, thus guarding against the link being released or the cars becoming uncoupled by jolts or jars.

Having thus fully described my invention, 65 what I claim as new, and desire to secure by Letters Patent, is—

1. The combination, in a car-coupler, of a draw-head with a pivoted weighted catch, a pivoted latch for engagement therewith, and 70 the coupling-pin, all constructed and arranged to operate substantially as and for the purpose described.

2. The combination, in a car-coupler, of the pivoted latch B, having the coupling-pin pivoted to its front end and its rear end provided with a projection, and the weighted catch C, with its head adapted to rest under the projection on the latch when the pin is down, all substantially as and for the purpose set forth. 80

In testimony that I claim the foregoing as my own I affix my signature in presence of two witnesses.

EDWARD W. GRANT.

Witnesses:

EDWARD P. ALLEN,
WALTER BARLOW.
